DESIGN FOR A SHOE

James D. Adams, Pittsfield, N. H.

Application September 26, 1945, Serial No. 122,347

Term of patent 14 years

(Cl. D7—7)

To all whom it may concern:

Be it known that I, James D. Adams, a citizen of the United States, residing at Pittsfield, in the county of Merrimack and State of New Hampshire, have invented a new, original, and ornamental Design for a Shoe, of which the following is a specification, reference being had to the accompanying drawing forming a part thereof, in which:

Fig. 1 is a view in elevation of a shoe showing my new design, the heel being shown conventionally in dot and dash lines, and

Fig. 2 is a plan view of the same.

I claim:

The ornamental design for a shoe, substantially as shown and described.

JAMES D. ADAMS.
